UNITED STATES PATENT OFFICE

KURT PETER, OF NEW YORK, N. Y.

GAME

Application filed March 26, 1929. Serial No. 349,941.

This invention relates to amusement devices in general and particularly to an amusement device requiring not only skill of the players, but providing surprises for the participants of the game.

It consists of two or more stands provided with hinged platforms, adapted to normally support the players, and target members in front of the players equipped with a plurality of individual targets corresponding, in each stand, to the number of stands employed, and so arranged that their operation will cause the platforms to tilt, thereby precipitating the fall of the affected player.

The targets control the operation or rather the release of the platforms from their normal supporting position. The targets are electrically or mechanically grouped together in a predetermined fashion so as to form platform control fields corresponding to the number of platforms or stands employed. When a target in any one field is operated, the platform controlled by that field is released. The players not knowing which one of the targets controls their own platform upon which they stand may themselves cause their own platform to collapse. The actuation of the targets may be caused by throwing balls, shooting, or other means of hitting the targets.

The foregoing general description will be more fully apparent from the following specification and the accompanying drawings, forming part of my disclosure, but by no means intended to limit it to the actual showing, and in which

Figure 1 is a perspective view, illustrating a group of target stands,

Figure 2 is a typical cross sectional view through one of the stands, and

Figure 3 is an electric diagram showing the connections of individual targets and their grouping for platform controls.

In the figures, numeral 10 denotes a base upon which are mounted stands 11, comprising collapsible or hinged platforms 12, so arranged that they may swing or tilt downwards, thereby causing the player to fall upon the soft front portion 13 of platform 10. This front portion 13 is preferably made in the form of a spring mattress or any other ar-

rangement preventing injuries to the players when they are caused to fall thereupon.

In each stand there will be seen in front of the platform 12, a barrier 14, preferably provided with an opening through which balls 15 held ready by spring 16, may be made available to the players. Behind barrier 14 there will be seen a field in the form of a tray 17, adapted to catch the missiles thrown against the target members 18, provided with individual targets 19, 20, 21 and 22.

Referring to Figure 2, it will be seen that the individual targets comprise hinged discs which are restricted in their outward movement but are adapted to swing inwards and towards contact points 24, 25, 26 and 27. Target 22 will be seen electrically connected by means of conductor 28 to electro-magnetic member 29, from which leads a conductor 30 to an electric source of energy, indicated at 31, and from which leads conductor 31' to contact point 27.

When target 22 is hit, it makes contact with contact point 27, energizes electro-magnet 29, and causes the spring controlled armature 32 to recede into the solenoid. By thus receding, armature 32 releases spring controlled pawl 33 with the end of catch lever 34. The latter is hinged at 35 and provided with a retaining hook 36, which is normally engaged by gravity pawl 37, forming the extension of weighted lever 38 hinged at 39. This weighted lever 38 forms an extension of platform 12. Its weight, indicated at 40, is less than the average weight of a person standing upon platform 12. Therefore, when the electro-magnet draws in armature 32, the weight of the player causes platform 12 to swing downwards, and therefore precipitates the fall of the player upon the soft front portion 13 of platform 10.

The moment the weight of the player releases platform 12, the weight 40 brings lever 38 into its normal position, and pawl 37 is caught by hook 36 and armature 32, which was momentarily drawn in but immediately thereafter released, due to its normal position, again supports pawl 33. Thus, the arrangement is brought into normal position.

Lever 34 is supported by an expansion

spring provided near the pawl end 33 of its longer arm, and the upward movement of this arm induced by that spring is limited by a suitable construction at the fulcrum 35 of the lever, so that pawl 33 cannot swing beyond a position just clearing armature 32.

Referring to Figure 3, there will be seen the arrangement of grouping together the targets so that each chain or row of targets 10 is connected in parallel with each other and thereby enables any one player in any one of the stands to cause the fall of any one of the players in any one stand, including himself. In this figure, numeral 41 indicates the 15 source of energy, and numerals 42, 43, 44, 45 and 46, indicate the electro-magnets.

It will be observed that in this figure five electro-magnets are shown, indicating that any number of stands may be employed to 20 comprise a game. Consequently, a corresponding number of targets is shown for each stand. The targets and the contact points are illustrated diagrammatically only, and I shall mark only the electric conductors 25 connecting targets and contact points by numerals. Thus, numeral 42' indicates targets controlling electro-magnet 42, and numeral 42'' indicates the contact points cooperating with targets 42'. Numeral 43' indicates targets, and numeral 43'' indicates contact points controlling electro-magnet 43, etc.

It will be seen from Figure 3 that the targets and contact points are grouped horizontally with each other and each group controls 30 its respective electro-magnetic device. This grouping, however, may be readily changed to any desired arrangement so as to prevent any one player from knowing which one of the targets in front of him controls his own 35 platform. He then cannot know when hitting a target whether he himself will cause his platform to operate and precipitate his fall and the termination of his game.

While I have shown and described a game 40 particularly adapted for throwing balls against targets, and while I have illustrated only four stands in Figure 1, and indicated five stands in Figure 3, be it understood that the operation of the targets may be readily 45 changed from balls to any other missile; that even the basic principles of a shooting gallery may be employed for operating the targets, and that any number of stands can be arranged in rows or other grouping, as for 50 instance, in a circle, half circle or the like. Similarly, the operating and control mechanism shown in the drawing shall not be construed to limit my invention to the construction illustrated.

In Figures 1 and 2, there will be seen the 55 employment of a spring cushioned mattress. Be it understood, however, that air cushions, a water pool, or any other arrangement may be employed for incapacitating the falling player without injury to him.

In the foregoing description I have described one form of my game in which neither of the players is aware which one of the targets controls his own platform. However, in Figure 3 the diagram illustrates 70 that the successive rows of targets control the platforms in a defined way so that the upper row of targets control the mechanism, indicated at 42, or the first platform, the second row, the second platform, and so on. 75 In this arrangement each player knows which row of targets controls his platform, which enables him to avoid hitting the target controlling his platform, but he will seek hitting the targets controlling his opposing 80 players. Thus, a very interesting and amusing game may be fought.

From the foregoing it is evident that while I have mentioned various improvements, I shall not be limited thereto, and I therefore 85 reserve for myself the right to make such changes and improvements or alterations as may be required in employing my device in various localities and for various purposes.

I claim:—

1. An amusement device, comprising a plurality of operable player stands adapted to normally support a player, a stand releasing means provided with each stand, a plurality of targets facing each stand and operatively connected to certain of said releasing means.

2. An amusement device, comprising a plurality of operable player stands, normally in player supporting position, stand releasing means provided with each stand, a multiple target member facing each stand and consisting of a plurality of individual targets arranged in groups corresponding in numbers to that of the stands, each target group connected with and adapted to control the stand releasing means of one stand.

3. In an amusement device, a plurality of operable stands adapted to normally support players, stand releasing means provided with each stand, a multiple target member arranged in front of each and provided with a plurality of individual targets arranged in groups, and corresponding in numbers to the number of stands each group connected with and adapted to control the releasing means of one stand, control connections provided between the targets of each target group in such a way that when any one of the connected targets is operated, the releasing means of the corresponding stand will be actuated.

4. In an amusement device, a plurality of target stands provided with collapsible platforms normally adapted to support players, releasing means associated with each platform, target members arranged in front of each platform and having a plurality of individual targets, the number of targets on each target member corresponding to the

- number of platforms, connections arranged between the targets of one target member and corresponding targets of the other target members, to form chains or rows of connected targets, each chain or row controlling the releasing means of one of the platforms, whereby the operation of any one target of such chain will cause the collapse of the platform controlled by said chain or row.
- 10 5. In an amusement device, a plurality of target stands provided with collapsible platforms, normally adapted to support players, releasing means associated with each platform, electro-magnetic actuating means forming part of said releasing means, a target member for each target stand arranged in front of each platform and each provided with a plurality of individual targets corresponding in number to that of the platforms,
- 15 20 electric connections provided between corresponding targets of each stand and forming target groups, each of such target groups controlling the electro-magnetic actuating means of one platform, said targets in each group forming individual contact makers and breakers which, when brought into circuit closing position, will cause the energizing of said electro-magnetic means, which latter will in turn cause the collapse of the
- 25 30 corresponding platform, thereby overturning the player standing thereon.

In testimony whereof I affix my signature.
KURT PETER.
